Des. 222,329
Patented Oct. 19, 1971

222,329

CARPET TOOL

John F. Cuscovitch, 42 Woodbridge Ave.,
East Hartford, Conn. 06108

Filed July 13, 1970, Ser. No. 23,937

Term of patent 14 years

Int. Cl. D8—05

U.S. Cl. D8—15

FIG. 1

FIG. 2

FIG. 3

FIG. 4

FIG. 5

FIG. 1 is a top plan view of the carpet tool of the present invention;

FIG. 2 is a side elevation view of the carpet tool shown in FIG. 1;

FIG. 3 is a bottom plan view of the carpet tool in FIG. 1;

FIG. 4 is an end view of the carpet tool as seen from the left end in FIG. 2; and

FIG. 5 is an end view of the carpet tool as seen from the right end in FIG. 2.

I claim:

The ornamental design for a carpet tool, substantially as shown and described.
